UNITED STATES PATENT OFFICE

LE-ROY V. GORDON, OF CLEVELAND, OHIO

PADDING GUIDE FOR SEWING MACHINES

Application filed August 18, 1930. Serial No. 475,907.

This invention relates to padding guides for sewing machines, and more particularly to devices of this character adapted to be used in connection with the stitching of cover material to padding of ribbed or corrugated construction.

It is an object of the present invention to provide a padding guide for sewing machines which will spread the ribs of the padding and permit the cover material to be stitched down therebetween.

Another object of the invention is to provide a padding guide with a gauge for the cover material which will follow the groove between the ribs of the padding.

Another object of the invention is to provide a guide of the character described which will prevent the padding from fouling the needle of a sewing machine.

Other objects of the invention are to simplify and improve the construction and operation of devices of this character, to render the same inexpensive to manufacture, efficient in operation, and otherwise well adapted for the purposes set forth.

Other objects and features of novelty will be apparent as the following description proceeds, reference being had to the accompanying drawing, in which:

Figure 1 is a detail perspective view of the padding guide according to the present invention, showing the same in operation upon the padding;

Fig. 2 is an inverted plan view of the guide shown in Fig. 1;

Fig. 3 is a top plan view of the padding guide;

Fig. 4 is a vertical section taken along the line 4-4 of Fig. 3;

Fig. 5 is a rear view of the padding guide;

Fig. 6 is a front view of the same;

Fig. 7 is a detail elevation of a modified construction;

Fig. 8 is a top plan view of the same; and

Fig. 9 is a section through the padding showing the form it will take under the operation of the guide, the guide being omitted for clearness in illustration.

While the invention is of general application for the stitching of ribbed material, it

is particularly desirable for use in connection with padding for automobile seat backs. This padding is prepared in rough form, and then covered with upholstery finish material. The finish material is stitched down between the ribs of the padding, in order to smoothly cover the same. It is very desirable to make the stitching of the finish material as inconspicuous as possible.

The rough padding often has a comparatively loose surface which would catch in the ordinary presser foot of a sewing machine. This difficulty is increased by the resilient nature of the padding which is such that the ribs normally lie so close together as to prevent the entrance of the ordinary presser foot. The guide disclosed in the following description avoids the difficulties mentioned above and is otherwise admirably suited for this operation.

Referring more particularly to the drawing, the present invention is illustrated in connection with one type of padding, which is provided with a backing sheet 10 and a cover sheet 11. These sheets are connected by lines of stitching 12, the pockets between the sheets containing padding 13. To this padding it is desired to apply upholstery finish material 14, which should smoothly overlies the contour of the cover sheet 11 and be stitched to the sheets 10 and 11 adjacent the line of stitching 12.

The guide, according to the preferred embodiment of the invention, comprises a narrow bottom portion 15 having at one end 85 thereof a shank 16 provided with a socket 17 adapted to be secured to the presser bar 18 of an ordinary sewing machine, as by means of a set-screw 19. The bottom portion 15 projects forward substantially horizontally 90 from the shank 16, and terminates in an upturned parting portion 20. Flanges 21 and 22 are flared upwardly from the bottom portion 15 and diverge outwardly toward the rear thereof. The bottom portion 15 also 95 carries a depending flange 23, preferably smoothly curved and of greatest depth near the forward portion of the body. At the rear end of the bottom portion 15, the guide is provided with an aperture 24 which is 100

adapted to permit the passage of a needle 25 carried by a portion 26 of the customary sewing machine.

In operation, the upholstery finish material 14 is folded as at 27 and the fold is pressed down into the groove between the ribs of the padding. The padding and cover material are then fed to the sewing machine and are passed under the guide described above. 10 The depending flange 23 follows the seam 12 of the padding and the parting portion 20 passes between the padding ribs. Thus the bottom 15 flattens the padding adjacent to the seam 12, as shown in Fig. 9. The flange 15 21 engages the reversed side of the folded back cover sheet 14, and as the flare of the flange 21 increases toward the rear, the padding as well as the cover sheet 14 will be depressed as shown in Fig. 9, opposite the 20 needle 25 so as to prevent any interference therewith. The flange 22 will operate similarly on the cover sheet 11, and as the flare thereof increases toward the heel of the guide, the padding and cover 11 will be depressed to about the shape shown in Fig. 9. 25 At the same time, the fold 27 will engage the inner side of the flange 23 under the bottom portion 15 and so the flange will act as a gauge for the stitching by the needle 25. In 30 other words, the stitching and the fold of the cover sheet will be gauged by the flange 23 so that this line of stitching will be parallel to the line of stitching 12.

When a seam has been formed as above 35 described, the cover 14 will be pulled over the next rib in the padding and folded again to form the next seam. Thus the seam in the cover 14 is a concealed stitch and the fold 27, when the cover material is pulled over the 40 next rib, will be depressed into the groove immediately above the stitching 12. This arrangement provides a very neat appearing exterior for the completed upholstery.

As shown in Figs. 7 and 8, the flange 23 45 of Fig. 4 may be substituted by a disc or wheel 30, pivoted to the body 15 in such a manner as to depend below the body 15 substantially the same amount as the flange 23. The provision of the wheel will eliminate a certain 50 amount of friction and will be more desirable for some materials.

Figs. 7 and 8 illustrate a further modification, in that, in lieu of the socket 17, a flat portion 31 is provided for the shank 16 and 55 is perforated as at 32 so that the same may be bolted onto the stem of a different type sewing machine. Also the flange 33, corresponding to the flange 21, is recessed as at 34 to receive and clear the moving presser 60 foot employed on certain sewing machines. Thus the present invention is not limited to any type of sewing machine, or any special attachment thereto, but, instead, is generic to all types of sewing machines.

65 While two embodiments of the invention

have been illustrated and described in such detail as to enable any one skilled in the art to practice the invention, nevertheless it is to be understood that the invention is not to be limited to the details disclosed, other than as necessitated by the development of the prior art; but, instead, the invention embraces such embodiments of the broad idea as fall within the scope of the appended claims, it being obvious that various changes may be made in the disclosed embodiment without departing from the spirit of the invention.

Having thus described my invention, I claim:

1. A padding guide comprising a body having a parting portion at the front end thereof, a needle aperture to the rear of said parting portion, and flanges flared upwardly and outwardly away from said needle aperture. 80

2. A padding guide comprising a body having a parting portion at the front end thereof, a narrow bottom portion extending rearwardly from said parting portion, a needle aperture in said bottom portion, and flanges flared upwardly and outwardly away from said needle aperture. 85

3. A padding guide comprising a body having a parting portion at the front end thereof, a needle aperture to the rear of said parting portion, a depending flange between 95 said parting portion and said needle aperture, and flanges flared upwardly and outwardly away from said needle aperture.

4. A padding guide comprising a body having a parting portion at the front end 100 thereof, a narrow bottom portion extending rearwardly from said parting portion, a depending flange at one edge of said bottom portion, a needle aperture in said bottom portion, and flanges flared upwardly and outwardly away from said needle aperture. 105

5. A device for stitching cover material to padding having ribs with a seam therebetween, comprising a guide having a depending flange adapted to follow said seam, a bottom adapted to flatten the padding adjacent said seam, a needle aperture in said bottom, and flanges flared upwardly and outwardly away from said bottom portion to deflect said ribs away from said needle aperture. 110

6. A device for stitching a fold of cover material along a seam of ribbed padding, comprising a guide having a parting portion with a narrow bottom portion extending rearwardly therefrom, said bottom portion having a depending flange adapted to follow the seam, said bottom portion being adapted to flatten said padding adjacent said seam and having a needle aperture to one side of said flange, said bottom portion and said flange forming a corner adapted to receive said fold, align the same with said seam and gauge the needle therefrom. 115

7. A device for stitching a fold of cover material along a seam of ribbed padding, 120

125

130

comprising a guide having a parting portion with a narrow bottom portion extending rearwardly therefrom, said bottom portion having a depending flange adapted to follow the seam, said bottom portion being adapted to flatten said padding adjacent said seam and having a needle aperture to one side of said flange, said bottom portion and said flange forming a corner adapted to receive said fold, align the same with said seam, and gauge the needle therefrom, and a pair of flanges extending upwardly and outwardly from the edges of said bottom portion, said flanges being flared outwardly from said parting portion and diverging away from said needle aperture to depress and deflect said padding and the free portions of said cover material away from said needle aperture.

20 8. A padding guide comprising a body having a parting portion at the front end thereof, a needle aperture to the rear of said parting portion, a wheel pivoted to said body between said parting portion and said needle aperture, and flanges flared upwardly and outwardly away from said needle aperture.

9. A padding guide comprising a body having a parting portion at the front end thereof, a narrow bottom portion extending rearwardly from said parting portion, a wheel pivoted to one side of said body adjacent said parting portion, said wheel depending below said narrow bottom portion, a needle aperture in said bottom portion, and flanges flared upwardly and outwardly away from said needle aperture.

40 10. A padding guide comprising a body having a parting portion, a narrow bottom portion extending rearwardly from said parting portion, and a wheel pivoted to said body, said wheel depending below said narrow bottom portion.

45 11. A padding guide comprising a body having a parting portion, a narrow bottom portion extending rearwardly from said parting portion, a needle aperture in said narrow bottom portion, and a wheel pivoted to said body, said wheel depending below said narrow bottom portion.

50 50 In testimony whereof, I hereunto affix my signature.

LE-ROY V. GORDON.
